UNITED STATES PATENT OFFICE.

WALTER V. TURNER, OF WILKINSBURG, AND ROBERT H. BLACKALL, OF EDGEWOOD PARK, PENNSYLVANIA, ASSIGNEES TO THE WESTINGHOUSE AIR BRAKE COMPANY, OF PITTSBURG, PENNSYLVANIA, A CORPORATION OF PENNSYLVANIA.

AIR-BRAKE.

No. 907,200.

Specification of Letters Patent.

Patented Dec. 22, 1908.

Application filed May 21, 1904. Serial No. 209,068.

To all whom it may concern:

Be it known that we, WALTER V. TURNER and ROBERT H. BLACKALL, citizens of the United States, residing, respectively, in Wilkinsburg and Edgewood Park, both in the county of Allegheny and State of Pennsylvania, have invented a certain new and useful Improvement in Air-Brakes, of which the following is a specification.

10 This invention relates in general to automatic air brakes, and more particularly to apparatus of this character as applied to motor cars, locomotives, or other vehicles where a plurality of such vehicles are adapted 15 to be coupled up together in a train, two or more of such vehicles forming the train being provided with the usual automatic air brake equipment having a source of air pressure, such as a main reservoir, and one or more 20 controlling valves, usually one at each end of the car, for operating the brakes on all the cars of the train from any one of said valves. Heretofore in service of this character, such as electrically propelled cars and trains operating on the multiple-unit control system, each car has usually been provided with an air pump, a main reservoir connected to a motorman's brake valve at each end of the car, the ordinary auxiliary reservoir, triple 25 valve and brake cylinder, and the train pipe running through the train. A coupling for the main reservoir pipes between the cars has also been employed for establishing communication between the main reservoirs of 30 all the cars and thereby utilizing all of the pumps in supplying the compressed air for the air brake system. With this arrangement, however, it has been found necessary to provide some means for connecting up all 35 of the pump governors in order to secure a simultaneous action of the same in controlling the several pumps.

One of the objects of this invention is to render the use of such governor connecting means and the main reservoir pipe couplings unnecessary and to provide an improved apparatus by means of which the supply of air from the main reservoir to the train pipe on a plurality, or on each and all of the cars of the 45 train, may be controlled by the manipulation of any one of the controlling valves, or motorman's brake valves, on the train.

Another object is to provide an improved feed valve device and connections with a mo-

55 torman's brake valve, whereby said feed valve device is in constant open communication with the main reservoir pressure, and communication from the regulating part of the feed valve to the train pipe is controlled by the brake valve.

60 A further object is to control the feed valve device by means of the auxiliary reservoir pressure when the brake valve is in lap position, and also to supply air from the feed valve directly to both the auxiliary reservoir 65 and the train pipe.

70 Still another object is to be able to vary the relative rates at which the air is supplied from the feed valve to the auxiliary reservoir and to the train pipe; and another object is 75 to secure a rapid recharge of the auxiliary reservoirs when the brakes are released.

With these and other objects in view the invention comprises certain new combinations and improved features of construction 75 as hereinafter more fully set forth.

In the accompanying drawings, Figure 1 is a diagrammatic view showing an air brake equipment embodying our invention and applied to two motor cars coupled up together 80 in a train; Fig. 2 a sectional view of a brake valve feed valve device and triple valve device connected up in accordance with our invention, the section of the triple valve being indicated by line x—x of Fig. 5; Fig. 3 a plan view 85 of the brake valve seat showing its ports and passages; Fig. 4 a face view of the rotary valve of the brake valve; Fig. 5 a plan view of the main slide valve seat of the triple valve device; and Fig. 6 a face view of the 90 main slide valve.

According to the construction herein shown to illustrate the invention, a plurality of motor cars of the train are each provided with a main reservoir 1, motor driven air 95 pump 2, pump governor 3, main reservoir pipe 4 leading to the motorman's brake valve or valves 5, train pipe 6 adapted to be coupled up through the train and connected to the triple valve device 7, auxiliary reservoir 8, 100 brake cylinder 9 and feed valve device 10, the latter being connected by pipe 11 with the triple valve device.

The motorman's brake valve, which, as shown, is of the rotary type, comprises a casting having port 12 connecting the main reservoir pipe 4 with the chamber above the rotary valve 18, while in the valve seat the lo-

cated the train pipe port 13 leading to train pipe 6, exhaust port 40 leading to the atmosphere, ports 17 and 41 connecting with the train pipe space, and port 15 leading to the feed valve device 10. The rotary valve 18 is provided with port 39 and cavities 16 and 37.

The feed valve device is of the slide valve type and has its valve chamber 19 in open communication with the main reservoir through any convenient connection, such as port 14 leading to the chamber of the brake valve. In this way the slide valve 23 is constantly subject to main reservoir pressure and applies air directly to the train pipe through ports 25, 28, 26 and 13 when the slide valve is open. At the same time port 24 registers with port 27 and applies air to the train pipe through ports 29 and 15, and 20 to the auxiliary reservoir through pipe 11 and to the diaphragm chamber 34 connected to said pipe. The regulating or diaphragm valve 35 is operated by the opposing pressures of the diaphragm chamber and the adjustable spring 36 for controlling the release of compressed air from the chamber 21 in the rear of the movable abutment or piston 20, and communication from the diaphragm chamber 34 to the train pipe is established through ports 15, 16, 17 and 13 when the brake valve is in running position.

According to the present construction the triple valve device 7 comprises the piston 42, stem 43 for operating the main slide valve 44 and graduating slide valve 45 in response to variations in train pipe pressure for controlling the supply of air to and its release from the brake cylinder. In the main slide valve seat are located the brake cylinder port 47, exhaust port 50, feed port 51 leading from the pipe 11 and the feed valve device, quick action port 57 leading to the small emergency piston 50 for operating emergency valve 59 and check valve 61, and quick recharging or feed port 56 connected with the emergency check valve chamber 61. The main slide valve is provided with service port 46, emergency port 48, exhaust ports 49, 53 and 54, and feed port 55, while the graduating slide valve has a cavity 52 and is adapted to control the ports 46, 49, 53 and 55 of the main slide valve.

The operation of the improved apparatus is as follows:—When two or more cars provided with this equipment are coupled up together in a train, the brakes of all the cars are controlled by the manipulation of a single brake valve, usually the one at the head end of the train, while all the other brake valves are set in lap position, as indicated in Fig. 1. The system being charged to normal pressure, the handle of the head brake valve stands in running position, and the train pipe is in open communication with the diaphragm chamber 34 of the feed valve device

through ports 13, 17, 16 and 15, so that the feed valve operates to maintain the train line charged to the normal degree of pressure, at which time the spring 36 is compressed sufficiently to allow the pin valve 35 to close, and as the main reservoir pressure leaks around the piston 20 and equalizes on its opposite sides the spring 22 moves the slide valve 23 to its closed position, thereby cutting off the flow from the main reservoir to the train pipe. If the train pipe pressure should diminish below normal on account of leakage the force of the spring 36 would preponderate over the pressure on diaphragm 33 and slightly open the pin valve 35, thereby permitting a flow of air from the chamber 21 through passage 32 to the train pipe. The higher main reservoir pressure acting on the opposite side of piston 20 immediately causes the piston and slide valve 23 to move over against the pressure of the spring 22 and open the port 25 for replenishing the train pipe. It is now evident that the device operating as thus far described, and without additional or further connections, will perform in an efficient manner the usual function of a standard feed valve device. With the device connected up in this way, the same feed valve may also be used to automatically control the supply of air from the main reservoir to the train pipe when its brake valve is on lap and the brakes are being operated from another brake valve on the train, and according to the present construction this result is secured by means of the additional ports 24 and 27 and connection 11 with the triple valve device. When the brake valve with which the feed valve is connected is set in lap position, the port 15 leading from the diaphragm chamber 34 to the train pipe is closed and the regulating device or diaphragm is then governed by the auxiliary reservoir pressure, which communicates therewith through the pipe 11, and ports 51 and 55 when the triple valve is in release position, as indicated in Fig. 2. When an ordinary service application of the brakes is desired, the brake valve is turned to service position, in which port 15 is closed and the train pipe space or port 13 is opened to the atmosphere through cavity 37, restricted extension 38 and exhaust port 40, thereby reducing the train pipe pressure and causing the movement of the triple valve to service position. The first part of the movement of the triple piston and graduating slide valve closes the brake cylinder exhaust ports 49 and 53, and the port 55 in the main slide valve and uncovers port 46, while the further movement draws the main slide valve to its service position, in which port 46 registers with brake cylinder port 47 and port 56 is closed. As the brake valve is turned the triple piston and graduating valve move to lap position and all ports through the triple valve are closed. In the mean-

time all of the feed valve devices will also remain closed, since there is no outlet from the diaphragm chamber, consequently the pressure on opposite sides of piston 20 will be equalized and the spring 22 retains the slide valve 23 in its closed position.

When the brake valve is moved to release position, air from the main reservoir flows to the train pipe through ports 39 and 41 and forces the triple valve to release position. The cavity 16 in the rotary valve 18 may be arranged to connect ports 5 and 17 in full release position as well as in running position, as indicated, so that upon a release of the 15 brakes by moving the brake valve to either full release or running position the train pipe is put into communication with port 15 and the regulating or diaphragm chamber 34, and since at this moment the train pipe pressure 20 is below normal the pin valve 35 is immediately opened by the spring 36, thereby permitting air which is confined at a higher pressure in chamber 21 to flow to the train pipe, so that the main reservoir pressure acting on 25 the opposite side of piston 20 immediately moves the slide valve 23 to open the feed ports 25 and 27. In the case of the feed valve device which is attached to the operating 30 brake valve, air then flows from the main reservoir through ports 25, 28 and 26 to the train pipe, and also through ports 24, 27, 29, and 15 to the train pipe, and through pipe 11 to port 51 of the triple valve. As the triple valve has now moved to release position port 35 51 communicates with the auxiliary reservoir through port 55 in the main slide valve, and air from the main reservoir is therefore being supplied through one port of the feed valve to both the train pipe and auxiliary 40 reservoir, and through another port to the train pipe thereby securing a quick recharge of both train pipe and auxiliary reservoir. In the case of the feed valve devices on the other cars where the brake valves are set in 45 lap position and the port 15 closed, the feed valve remains closed until the triple valve of that car moves to release position, at which time communication is established from the auxiliary reservoir through ports 55, 51 and 50 pipe 11 to the diaphragm chamber 34, thereby causing the feed valve to open and supply air from the main reservoir on that car through ports 25, 28 and 26 to the train pipe and through ports 24, 27, 29 and pipe 11 to 55 the diaphragm chamber and the auxiliary reservoir. By this means, the pressure in all of the auxiliary reservoirs will be increased at substantially the same rate as the train pipe, the excess of air which is being supplied to the train pipe through ports 15, 16 and 17 at the operating brake valve, which is in running position, being only sufficient to hold the triple valves in release position. These feed valves on the other cars remain open 60 and continue to supply air to the train pipe

and auxiliary reservoir until the pressure in the auxiliary reservoir which now acts upon the regulating diaphragm 33 rises to normal standard pressure, which compresses the spring 36 and closes valve 35, thereby allowing the main reservoir pressure to equalize around piston 20 and close the feed valve. From this it will be seen that when the brake valve is in lap position the feed valve device is controlled by the auxiliary reservoir pressure. 70

Another means, such as feed port 56, of large capacity, may be provided for insuring a rapid recharge of the auxiliary reservoirs and for preventing the train pipe pressure 80 from increasing more rapidly than that of the auxiliary reservoirs, especially at the time that the brake valve is in release position, this port preferably being arranged so as to be open when the triple valve is in release position, but closed in other positions, and also provided with a check valve to prevent back flow from the auxiliary reservoir to the train pipe. By connecting this port to the emergency valve chamber 61 of the standard 85 quick action triple valve device the check valve 61 will perform both functions and an additional check valve will not be required. 90

In order to be able to secure a prompt application of the brakes at any time, even directly after a release, and during the time that the system is being recharged, it is important that not only should the auxiliary reservoirs be recharged rapidly, but that the auxiliary reservoir pressure should be nearly 100 equal to that of the train pipe, so that the instant the operating brake valve is thrown to service application position and the additional feed to the train line through the port 15 of its feed valve is cut off, the further supply of air through each feed valve to the train pipe will not be sufficiently greater than the further supply through the feed valve to the auxiliary reservoir, to prevent the immediate movement of the triple valves 105 to service position in response to the reduction in train pipe pressure that is made at the brake valve. With the apparatus as shown, it will be noticed that the instant the triple valve pistons start to move from release to 110 service position the port 55, and consequently communication from the auxiliary reservoir to the diaphragm chamber of the feed valve device, is cut off, and as the pressure readily equalizes around the pistons 20 115 the feed valves will immediately close. By means of this construction all of the main reservoirs and pumps on the several cars are utilized in supplying air through their respective feed valves to the train pipe and 120 auxiliary reservoirs and the pressure is rapidly and uniformly restored after each release of the brakes, so that the same may be immediately re-applied and released as often as 125 desired. 130

By turning the brake valve to emergency position, in which the large cavity 37 is in full register with ports 13 and 40, a sudden reduction of train pipe pressure to the atmosphere causes the movement of the triple valve to emergency position, in which port 57 is opened to the auxiliary reservoir for actuating the emergency piston 58 and valve 59 in the usual manner, and port 48 registers with brake cylinder port 47 while the feed port 56 is closed.

It is sometimes desirable to be able to reduce the pressure in the brake cylinder without wholly releasing the same, and in order to secure this result in the present apparatus it is only necessary to provide a restricted opening as at 31 in the passage from feed port 25 to the train pipe, whereby the rate of feed to the train pipe will be less than that to the auxiliary reservoir when the brake valve is returned from running to lap position.

When the brakes are applied, and it is desired to reduce the brake-cylinder pressure a certain amount or to produce a graduated release of the same, the brake valve is turned to running or full release position for a moment, which is sufficient to open the first feed valve and raise the train pipe pressure enough to move the triple valves to release position, the brake valve then being turned back to lap position. The movement of the triple valves to release position causes each of the respective feed valves to open as before explained, and air is then supplied from each main reservoir through the restricted port to the train pipe and through a larger port to the auxiliary reservoir, consequently the auxiliary reservoir pressure soon preponderates and causes the triple piston and small slide valve to move back sufficiently to close port 55 and disconnect ports 49 and 53 in the main slide valve, thereby cutting off the exhaust from the brake cylinder and closing the feed valves. Further graduated reductions may be made in the brake cylinder pressure by repeating this operation, so that the braking pressure may be graded down to any point desired, while a complete release may be secured at any time by turning the brake valve to release or running position, in which the additional supply of air through port 15 to the train pipe at the head feed valve is sufficient to hold the triple valves in release position.

In case it is desired to cut out or dispense with the feature of graduating the release, it is merely necessary to provide means for securing a more rapid feed to the train pipe than to the auxiliary reservoir, and this may be conveniently done by turning cock 30 so as to close the feed port 27 and open a larger port 28 for feeding the train pipe passage 26. Then only the air which leaks past the piston 20 and passes the diaphragm valve 35 will be supplied to the auxiliary reservoir through

pipe 11, and consequently a greater supply will always be furnished through ports 25, 28 and 26 to the train pipe when the feed valve is open. From this it will be apparent that if desired the ports 24 and 27 and the cock 30 may be dispensed with without losing the advantage of being able to control the operation of all the feed valves from any one of the brake valves on the train. It will also be evident that either the ports 24 and 27 with pipe 11 or the feed port 56 in the triple valve, or both, may be used for securing the rapid recharging of the auxiliary reservoir upon a release of the brakes.

Having now described our invention, what we claim as new and desire to secure by Letters Patent is:—

1. In an air brake, the combination with a main reservoir, brake valve and train pipe of a valve for controlling communication from the main reservoir to the train pipe, a regulating device for controlling said valve according to the train pipe pressure, and means operated by the brake valve for opening and closing communication from the train pipe to said regulating device.

2. In an air brake, the combination with a main reservoir, brake valve and train pipe of a valve for controlling the supply of air to the train pipe, a piston connected thereto and exposed on one side to main reservoir pressure, a regulating valve and diaphragm for controlling the pressure upon the opposite side of said piston, and means operated by the brake valve for controlling communication from the train pipe to said regulating diaphragm.

3. In an air brake, the combination of a valve for controlling the supply of air to the train pipe, a piston subject to fluid pressure for operating said valve, a regulating device for controlling the pressure on one side of said piston, and a brake valve having a port or ports for controlling communication from the train pipe to said regulating device.

4. In an air brake, the combination of a valve for controlling the supply of air to the train pipe, a piston subject to fluid pressure for operating said valve, a regulating device for controlling the pressure on one side of said piston, and a brake valve having a port or ports for opening communication from the train pipe to said regulating device when in running position.

5. In an air brake, the combination of a valve for controlling the supply of air to the train pipe, a piston subject to fluid pressure for operating said valve, a regulating device for controlling the pressure on one side of said piston, and a brake valve having means for opening communication from the train pipe to the regulating device in running position and for closing the same in lap position.

6. In an air brake, the combination with a main reservoir and train pipe of a valve and

- 6 piston constantly subject to the main reservoir pressure for controlling the supply of air to the train pipe, a regulating diaphragm and valve for controlling the release of air from the opposite side of said piston, and a 5 brake valve having means for opening and closing communication from the train pipe to said regulating diaphragm.
7. In an air brake, the combination with a main reservoir, train pipe and auxiliary reservoir of a valve for controlling the supply of air to the train pipe, a piston for actuating said valve, a regulating device for controlling the pressure upon one side of said piston, and 10 means operated by an increase in train pipe pressure for opening communication from the auxiliary reservoir to the regulating device.
8. In an air brake, the combination with a main reservoir, train pipe and auxiliary reservoir of a valve for controlling the supply of air to the train pipe, a piston subject to the main reservoir pressure for actuating said valve, a regulating diaphragm and valve 15 for releasing air from one side of said piston, and means operated by an increase in train pipe pressure for opening communication from the auxiliary reservoir to the regulating diaphragm.
9. In an air brake, the combination with a main reservoir, train pipe and auxiliary reservoir, of a valve for controlling the supply of air to the train pipe, a piston for actuating said valve, and a regulating device subject to the pressure of the auxiliary reservoir for controlling the pressure upon 20 one side of said piston.
10. In an air brake, the combination with a main reservoir, train pipe and auxiliary reservoir of a valve for controlling the supply of air to the train pipe, a piston subject to the main reservoir pressure for actuating said valve, a regulating diaphragm and valve 25 for releasing air from one side of said piston to the auxiliary reservoir.
11. In an air brake, the combination with a main reservoir, train pipe, auxiliary reservoir and triple valve, of a valve for controlling the supply of air to the train pipe, a piston for actuating said valve, a regulating device for controlling the pressure upon 30 one side of said piston and means operated by the movement of the triple valve to release position for opening communication from the auxiliary reservoir to said regulating device.
12. In an air brake, the combination with a main reservoir, train pipe, auxiliary reservoir and triple valve, of a valve for controlling the supply of air to the train pipe, a piston subject to main reservoir pressure for actuating said valve, a regulating diaphragm and valve for releasing air from one side of 35 said piston, and ports controlled by the triple valve for opening communication from the auxiliary reservoir to the regulating device.
13. In an air brake, the combination with a main reservoir, brake valve, train pipe and auxiliary reservoir, of a valve for controlling the supply of air to the train pipe, a piston for actuating said valve, a regulating device for controlling the pressure upon one side of said piston, and means for opening and closing communication from the 40 regulating device to the train pipe and to the auxiliary reservoir.
14. In an air brake, the combination with a main reservoir, brake valve, train pipe and auxiliary reservoir, of a valve for controlling the supply of fluid to the train pipe, a regulating device for controlling said valve, means for opening and closing communication from the regulating device to the train pipe and from the regulating device to the auxiliary reservoir.
15. In an air brake, the combination with a main reservoir, brake valve, train pipe and auxiliary reservoir, of a valve for controlling the supply of fluid to the train pipe, a regulating device for controlling said valve, means operated by the brake valve for controlling communication from the regulating device to the train pipe, and means operated by variations in train pipe pressure for controlling communication from the regulating device to the auxiliary reservoir.
16. In an air brake, the combination with a main reservoir, brake valve, train pipe, auxiliary reservoir and triple valve, of a valve for controlling the supply of air to the train pipe, a regulating device for controlling said valve, the brake valve having ports for opening communication from the regulating device to the train pipe in running position, and the triple valve having ports for controlling communication from the auxiliary reservoir to said regulating device.
17. A feed valve device for air brakes comprising a valve having ports for supplying air from the main reservoir to both the train pipe and the auxiliary reservoir, and a regulating device subject to the train pipe or auxiliary reservoir pressure for controlling said valve.
18. In an air brake, the combination with a main reservoir, brake valve and train pipe of a valve device governed by the auxiliary reservoir pressure for controlling the supply of air to the train pipe.
19. In an air brake, the combination with a main reservoir, brake valve and train pipe of a valve device governed by the auxiliary reservoir pressure for controlling the supply of air to both the auxiliary reservoir and the train pipe.
20. In an air brake, the combination with a main reservoir, brake valve and train pipe, of a valve for controlling the supply of air to the train pipe and to the auxiliary reservoir.

- through separate passages, a regulating device for controlling said valve, and means for causing either the train pipe pressure or the auxiliary reservoir pressure to act on said regulating device.
21. In an air brake, the combination with a main reservoir, brake valve and train pipe, of a valve for controlling the supply of air to the train pipe and to the auxiliary reservoir
- 10 through separate passages, a regulating device for controlling said valve, means operated by the brake valve for opening and closing communication from the train pipe to the regulating device, and a triple valve device
- 15 for controlling communication from the auxiliary reservoir to said regulating device.
22. In an air brake, the combination with a main reservoir, brake valve and train pipe, of a feed valve device having a port for supplying air to the train pipe, and another port for supplying air to both the train pipe and auxiliary reservoir.
23. In an air brake, the combination with a main reservoir, brake valve and train pipe, of a feed valve device having a port for supplying air to the train pipe, a second port for supplying air to both the auxiliary reservoir and train pipe when the brake valve is in running position, and means for closing the second supply to the train pipe when the brake valve is moved to lap position.
24. In an air brake, the combination with a main reservoir, brake valve and train pipe, of a feed valve device having a port for supplying air to the train pipe, a second port of larger capacity for supplying air to both the auxiliary reservoir and train pipe when the brake valve is in running position, and means for closing the second supply to the train pipe
- 40 when the brake valve is moved to lap position.
25. In an air brake, the combination with a main reservoir, brake valve and train pipe, of a feed valve device having a port for supplying air to the train pipe, a second port or passage for supplying air to both the train pipe and the auxiliary reservoir, and means for adjusting the relative capacities of said passages.
- 50 26. In an air brake, the combination with a main reservoir and train pipe, of a feed valve device for controlling the supply of air from the main reservoir to the train pipe and the auxiliary reservoir through separate passages, and a triple valve device having a graduating valve for controlling the brake cylinder exhaust and the passage from the feed valve to the auxiliary reservoir.
- 60 27. In an air brake, the combination with a train pipe, auxiliary reservoir and triple valve, of a feed passage leading from the train pipe around the triple valve piston to the slide valve seat and adapted to be open when the valve is in release position but closed by the slide valve in all other positions.
28. In an air brake, the combination with a train pipe, auxiliary reservoir and triple valve, of a feed passage leading from the train pipe around the triple valve piston to the slide valve seat and adapted to be open when the valve is in release position but closed by the slide valve in service applications, and a check valve for preventing back flow through said feed passage.
- 70 29. In an air brake, the combination with a train pipe, auxiliary reservoir and a quick action triple valve having an emergency valve and check valve for venting the train pipe in emergency applications, of a feed port or passage leading from the emergency valve chamber above the check valve to the auxiliary reservoir.
- 75 30. In an air brake, the combination with a train pipe, auxiliary reservoir and a quick action triple valve having an emergency valve and check valve for venting the train pipe in emergency applications, of a feed port or passage leading from the emergency valve chamber above the check valve to the slide valve seat and adapted to be open when the slide valve is in release position, but closed by said valve in service application position.
- 80 31. In a fluid pressure brake, the combination with a train pipe, auxiliary reservoir, and brake cylinder, of means for effecting a gradual release of the brakes comprising a valve device governed by auxiliary reservoir pressure for supplying fluid to the auxiliary reservoir.
- 85 32. In a fluid pressure brake, the combination with a train pipe, auxiliary reservoir and brake cylinder, of a valve device governed by auxiliary reservoir pressure for supplying fluid to the auxiliary reservoir and a triple valve having means for controlling communication from the auxiliary reservoir to said valve device.
- 90 33. In a fluid pressure brake, the combination with a train pipe, auxiliary reservoir and brake cylinder, of a valve device governed by auxiliary reservoir pressure for supplying fluid to the auxiliary reservoir and a triple valve having a port adapted to open communication from the valve device to the auxiliary reservoir in normal release position.
- 95 34. In a fluid pressure brake, the combination with a train pipe, auxiliary reservoir and brake cylinder, of a valve device for controlling a supply of fluid to the auxiliary reservoir, a regulating mechanism therefor, and a triple valve device having means for controlling communication from the auxiliary reservoir to said regulating mechanism.
- 100 35. In a fluid pressure brake, the combination with a main reservoir, train pipe, auxiliary reservoir and brake cylinder, of a valve device for controlling a supply of fluid from the main reservoir to the auxiliary reservoir, a regulating mechanism therefor, and a triple valve device having means for controlling communication from the auxiliary reservoir to the auxiliary reservoir.
- 105 110 115 120 125 130

communication from the auxiliary reservoir to said regulating mechanism.

36. In a fluid pressure brake, the combination with a brake valve, auxiliary reservoir and train pipe of a feed valve device having ports for supplying air to the auxiliary reservoir and to the train pipe, when the brake valve is in running position, and means for reducing the rate of feed to the train pipe for

effecting a gradual release when the brake valve is moved to lap position.

In testimony whereof we have hereunto set our hands.
